SPARKING TOP

Irving C. Brown, Baltimore, Md.

Application May 20, 1933. Serial No. 672,074

10 Claims. (Cl. 46—14)

This invention relates to a toy and more particularly to a sparking top.

One object of this invention is to provide a manually operable top which will emit a shower 5 of sparks when operated.

Another object of this invention is to provide a simple sparking top which is cheap to manufacture, and which may be operated with perfect safety by children.

10 Various other objects of the invention will be apparent from the following description and appended claims. In the drawings which illustrate my preferred embodiments, it being understood that the invention is not limited to the specific 15 forms selected for the purposes of illustration,

Fig. 1 shows the top held in the hand for operation,

Fig. 2 is a top plan view,

Fig. 3 is a side elevation of my novel top, the 20 head of the pivot screw being cut away,

Fig. 4 is a central section on line 4—4 of Fig. 3,

Fig. 5 shows a side elevation of a modified form, with the pivot screw broken away,

Fig. 6 is a central section thereof,

25 Fig. 7 is a central section of another modification.

Referring to the drawing wherein like characters indicate like parts, my novel top comprising a grooved pulley 7, made of wood, phenolic condensation product or other material having a flexible element, preferably a cord 9 secured to or adjacent to the axle 10. As seen in Fig. 4 the 30 groove in the pulley is offset to one side of pulley 7. A pivot pin such as a wood screw 8 projects from one side of pulley 7, the pivot pin being in alignment and forming in effect a continuation of the axle 10.

A momentum member in the form of a disk 11 is loosely swiveled on the pivot pin 8. The entire 40 assembly is so constructed that the mass of the parts is substantially the same on opposite sides of the axle 10, that is, the weight of disk 11 plus that of the intermediate disk 26 equals that of pulley 7. In this way the entire top is balanced 45 and may wind and unwind on the string 9 without tumbling.

The proximate faces of disk 11 and intermediate disk 26 are provided with coacting sparking elements. In the form shown in Figs. 1 to 4, the 50 disk 11 is radially slotted from one edge as at 15,

and a pencil of pyrophoric material 13 is mounted in a socket 14 in the slot 15. The saw slot 15 is sprung slightly open as by a screwdriver to allow the pyrophoric material to enter its socket, and to provide a tension grip to maintain its position. 55

Furthermore, this simple mounting allows the pencil 13 to be adjusted to compensate for wear, by merely springing the slot open and moving the pencil inwardly; also a new pencil 13 may be easily inserted in the same manner, this adjustment 60 or replacement being accomplished without disassembling the top.

On the adjacent flat face of intermediate disk 26, a disk or strip of abradant material such as carborundum paper 12 is mounted, whereby 65 sparks are emitted by the relative rotary movement of pyrophoric pencil 13 and paper 12.

It will be noted that the pivot bearing of the momentum disk 11 comprises a bearing portion 17 closely adjacent to the intermediate disk 26 of 70 pulley 7, the outer bearing portion being cut away as at 16. This cut-away portion 16 is preferably on the opposite side of disk 11 from the pyrophoric pencil 13. This cut-away portion 16 gives the disk 11 a tendency to move the pencil 13 toward 75 the pulley 7, due principally to the mass or weight of disk 11 above the pivot pin being supported only at a point close to pulley 7. This unsupported mass tends to tilt momentum disk 11 to the dotted line position of Fig. 4. The narrow bearing 17 80 allows momentum disk 11 to assume angular positions, as shown.

The operation of the sparking top is as follows: When thrown from the hand, the end of the string and being held, the top unwinds from the string and then winds up due to its momentum and returns to the thrower's hand. The momentum disk 11 however, is not directly driven by the string and derives its rotation solely by the relatively small friction of its narrow bearing 17 and the frictional contact of pyrophoric pencil 13 and abradant material 12. Thus the momentum disk 11 revolves considerably slower than pulley 7, and a shower of sparks are emitted. The pencil 13 intermittently engages the abrasive 12, the momentum disk 11 oscillating back and forth about its bearing 17. 85

Sparking occurs principally on the down stroke of the top and the rotation of disk 11 gradually approaches that of the main pulley 7. By the 90 95 100

time the top starts back up the string the disk 11 will have attained approximately the same speed as the pulley 7 and sparking ceases until the next downward stroke. Thus there is no danger of burning the hands, and children are not afraid of operating the top. The disk 11 rapidly oscillates about its narrow bearing 17 to cause the sparking but this oscillation is insufficient to cause tumbling of the top as a whole.

10 The intermediate disk 26 is preferably made of slightly smaller diameter than pulley 7 and disk 11 to prevent damage to this disk should the top strike the ground.

15 It has been found in actual practice that for effective operation the assembled top must balance when suspended by the string; that is, the weight on either side of the groove in pulley 7 should be the same. Furthermore, the relatively narrow bearing 17 for the momentum member 20 with the slot 16 so arranged that member 11 may oscillate slightly as well as rotate freely is an important feature.

25 In the modification shown in Figs. 5 and 6, the momentum disk 18 has two slots 19 carrying pencils 13 of pyrophoric material. These slots are not radial as they would weaken disk 18. The use of two pencils of pyrophoric material gives greater 30 sparking effect and in order to present a different surface on the abradant material, the pencils 13 are at different radial distances from the center.

35 A further modified form is shown in Fig. 7 wherein the main pulley comprises two members 20 and 21 rigidly secured to the screw member 8 in spaced relation. The string 9 winds upon the screw 8 in operating the top. In this form two pencils of pyrophoric material 22 are mounted on intermediate disk 21 and cooperate with a strip of abrasive 23 mounted on momentum disk 25. Disk 25 is normally pressed toward intermediate disk 21 by a light coil spring 24 placed between the head of screw 8 and a shoulder on momentum disk 25. This spring causes a continuous engagement of the sparking elements.

40 While I have shown and described in detail the preferred embodiments of my invention, it will be apparent that many changes may be made therein without departing from the spirit of the invention and the scope of the appended claims.

45 I claim:

1. A sparking toy of the class described comprising a pulley having an annular groove therein, a flexible member secured to said pulley in the groove thereof, a pivot pin projecting to one side of said pulley and substantially in alignment with the axis thereof, a momentum member loosely swiveled on said pivot pin, and sparking elements on the proximate faces of said pulley and momentum member, the weight of the pulley and momentum member being balanced on opposite sides of the point of connection of said flexible member, whereby the toy may wind and unwind on the flexible member without sidewise oscillation.

2. A sparking toy of the class described comprising a pulley having an annular groove therein providing a spool, a flexible member in the groove and adapted to wind and unwind on said spool, whereby said pulley may be rotated rapidly by a throwing motion, a pivot pin substantially in alignment with the pulley axis, a momentum member loosely pivoted on said pin whereby said member may rotate independently of and oscillate to a limited extent with respect to said pulley and means for causing sparking by the

relative oscillation and rotation of said pulley and momentum member.

3. A sparking toy of the class described comprising a pulley having an annular groove therein providing a spool, a cord in the groove adapted to wind and unwind on the spool, whereby said pulley may be rotated rapidly by a throwing motion, a pivot pin on said pulley in substantial alignment with the axis thereof, a momentum member loosely swiveled on said pivot pin, sparking elements mounted on the proximate faces of said pulley and momentum member, and means causing intermittent engagement of the sparking elements on the proximate faces of said pulley and momentum member during rotation of the pulley.

4. A sparking toy of the class described comprising a grooved pulley, a cord adapted to wind on said pulley to cause spinning thereof, a pivot pin on said pulley in substantial alignment with the spinning axis thereof, a momentum member freely pivoted on said pin, abradant material and a pencil of pyrophoric material on abutting faces of said pulley and momentum member, the bearing of said momentum member on said pin being loose to allow oscillation of said member, said member being overweighted to one side of the bearing to cause the member to oscillate.

5. A sparking toy of the class described comprising a pulley having a groove, a cord adapted to wind in said groove and spin said pulley, a pivot pin substantially in alignment with the spinning axis of said pulley, a momentum disk freely pivoted on said pin, a pencil of pyrophoric material projecting from the inner face of said disk, and abradant material on the abutting face of said pulley, the bearing of said momentum disk on said pin being cut back on the side thereof opposite the pyrophoric pencil, whereby said disk may oscillate toward the pulley.

6. A sparkling toy of the class described comprising a pulley having a groove, a cord adapted to wind in said groove and spin said pulley, a headed pivot pin substantially in alignment with the spinning axis of said pulley, a momentum disk freely pivoted on said pin, said disk having a radial slot therein, a pencil of pyrophoric material mounted in said slot and projecting therefrom toward said pulley and abradant material on said pulley for engagement by said pencil, the bearing in said disk being enlarged toward the headed end of said pivot pin to allow oscillation of said disk.

7. A sparkling toy of the class described comprising a top having a groove, a cord in said groove for spinning said top, a pivot pin in substantial alignment with the axis of said top, a momentum member loosely pivoted on said pin to allow limited oscillation of said member, sparking elements on the proximate faces of said top and momentum member, rotation being imparted to said momentum member from said top by intermittent engagement of said sparking elements due to oscillation of said member.

8. A sparkling toy of the class described which is adapted to be thrown from the hand and wind up and down on a held cord comprising a pulley having an annular groove therein, a cord secured to said pulley in the groove, a pivot pin projecting from one face of said pulley substantially in alignment with the axis thereof, a momentum disk loosely swiveled on said pivot pin, and sparking elements on the proximate faces of said pulley and disk, said disk having a narrow bearing on said pivot pin and being overbalanced to one side of its bearing to thereby cause engagement of said sparking elements.

9. A sparking toy of the class described comprising a spinning top, means for spinning said top about a substantially horizontal axis, a pivot pin on said top in alignment with the spinning axis thereof, a momentum member loosely and freely swiveled on said pivot pin, and sparking elements on proximate faces of said top and member, said momentum member being free to rotate on said pin and being overweighted on one side of its bearing on said pin to cause the member to oscillate on said pin. 10
10. A sparking toy of the class described comprising a grooved pulley, a cord adapted to wind on said pulley and cause spinning thereof, a momentum member loosely pivoted on said pulley, abradant material on one face of said pulley, and a pyrophoric pencil projecting from the proximate face of said momentum member, said momentum being provided with a slot in which said pencil is frictionally retained, adjustment of said pencil being accomplished by springing the slot open. 80 85
